(57) **CLAIM**

The ornamental design for a glove, as shown and described.

DESCRIPTION

FIG. 1 is a rear view of a first embodiment of a glove showing our new design;

FIG. 2 is a right side view thereof;

FIG. 3 is a left side view thereof;

FIG. 4 is a top side view thereof; and

FIG. 5 is a bottom side view thereof.

FIG. 6 is a rear view of a second embodiment of our design shown in FIG. 1;

FIG. 7 is a right side view thereof;

FIG. 8 is a left side view thereof;

FIG. 9 is a top side view thereof; and,

FIG. 10 is a bottom side view thereof.

The broken lines shown in the drawings are directed to features not claimed.
